UNITED STATES PATENT OFFICE.

ARON JOHNSON, OF BROOKLYN, NEW YORK.

APPARATUS FOR PACKING COMMINUTED MATERIAL.

Application filed April 18, 1921. Serial No. 462,406.

To all whom it may concern:

Be it known that I, ARON JOHNSON, a citizen of the United States, and a resident of the borough of Brooklyn, in the county of Kings, city and State of New York, have invented certain new and useful Improvements in Apparatus for Packing Comminuted Material, of which the following is a specification.

This invention relates to apparatus for packing ground or comminuted material into tubes, such as cork mixed with a binder, to form sticks commonly termed "cork sticks" which are baked while packed into tubes and from which sticks portions of predetermined thicknesses are cut to constitute a lining for closure caps of the crown type for receptacle closures, and it is the primary object of the invention to improve the general construction and arrangement of apparatus for this purpose to provide an apparatus of more simple and cheap structure and more efficient in operation.

It is the practice in apparatus of this character to provide a series of pockets arranged to receive material from a hopper and a series of tubes are movably supported with an end thereof brought into register with said pockets, plungers being provided to deliver material from the pockets into an end of the tubes as successive increments until the tubes are filled.

In the present invention instead of movably supporting a series of tubes and bringing the tubes with an end thereof successively in register with the material receiving pockets and delivering the material from the pockets as successive increments until the tubes are filled, the tubes are movably supported with opposite ends to have movement between two series of material receiving pockets and brought into register successively with said pockets, the tube support being intermittently moved so that the tubes are presented in successive sequence to the successive pockets to receive successive increments of material therefrom into opposite ends of the tubes, the material being delivered from the pockets by plungers the successive plungers having movement of progressively decreasing extent in delivering the material from the successive pockets.

It is a further object of the invention to provide an improved construction and arrangement of adjustable pockets, means be-

ing provided operable during the material delivering movement of the plungers to shut off the pockets from the hopper thereby preventing any delivery of the material in the pockets back into the hopper, and as the plungers are being moved to retracted position adjust the pockets to open said pockets to the hopper to receive material therefrom.

It is a further object of the invention to provide adjustable means to regulate the delivery of material from the hopper to the pockets.

Other objects and advantages will hereinafter appear.

In the drawings accompanying and forming a part of this specification Figure 1 is a side elevation, partly in section, of apparatus illustrating an embodiment of my invention.

Figure 2 is an end elevation looking at the right of Figure 1.

Figure 3 is a sectional side elevation taken on the line 3—3 of Figure 1 looking in the direction of the arrows.

Figure 4 is a perspective view of a train of gearing for actuating the operative mechanism of the apparatus.

Figure 5 is a plan view, partly in section, to illustrate the means for feeding the material into the opposite ends of the tubes and showing the method of feeding the material into the tubes.

Figure 6 is a sectional side elevation of the means to feed the material to the tubes and showing the parts in position with an increment of material fed into a tube and the material receiving pockets to which the material is fed from a hopper and shut off from the hopper.

Figure 7 is a view similar to Figure 6 but showing the parts in position previous to feeding an increment of material to a tube and the material receiving pocket positioned to receive material from the hopper.

Figure 8 is a perspective view of a material receiving pocket to which the material is delivered from a hopper and from which the material is fed into a tube.

Figure 9 is a perspective view of an actuator for a series of material feeding plungers.

Figure 10 is a perspective view of a plunger for feeding material from a pocket into a tube; and

Figure 11 is a perspective view of a support for a series of pockets arranged at an outlet of a hopper.

Similar characters of reference designate 5 like parts throughout the different views of the drawings.

In the embodiment of my invention illustrated in the drawings a pair of brackets 12 (Figure 11) are provided, each bracket 10 being mounted upon the ends of a pair of rods 13 in alined and spaced relation the rods being mounted in horizontal position in standards 14 and 15 mounted upon a base B. The brackets 12 have a segmental 15 portion 16 the outer curved walls of which are located below the outlets 17 of a hopper or a plurality of hoppers H for a material M, such as cork mixed with a suitable binder, said hopper outlets being mounted upon the brackets 12. The segmental portion 16 of each of the brackets 12 has a series of parallel recesses 19, in the present instance nine in number, arranged in an arc of a circle whose axis lies in the axis of a shaft 20 mounted in a depending portion of the brackets 12. Pockets in the form of tubes 21 (Figure 8) are rotatably mounted in the recesses 19, said pockets being arranged to receive material from the hopper outlets and 25 to be shut off from the hopper outlets in a manner and for a purpose to be hereinafter described.

As stated, it is an object of the invention to feed successive increments of material 35 in sequence from the successive pockets 21 into opposite ends of a tube 22, or a series of tubes presented in sequence to the successive pockets. For this purpose a support or carrier is provided to carry a series of 40 tubes in a horizontal position, one for each of the series of pockets carried by the bracket 12 with the opposite ends of the tubes in axial alinement with the pockets. This support is in the form of a turret or rotary 45 conveyer comprising a pair of heads 23 arranged with equidistantly spaced circumferentially disposed tube receiving recesses 23', the heads being fixed upon the shaft in spaced relation as shown in Figure 1.

The tube carrying conveyer is intermittently rotated by means of a gear 24 fixed 50 on the shaft 20 meshing with a pinion 25 fixed to a shaft 26 journalled in a bracket 27, a mutilated pinion 28 also being fixed 55 upon the shaft 26. The shaft 26 is intermittently rotated by a mutilated gear 29 co-operating with the mutilated pinion 28, said gear 29 being fixed on a shaft 30 journalled in the bracket 27. A pinion 31 on said 60 shaft 30 meshes with a pinion 32 fixed on a shaft 33, the latter shaft being driven from a suitable source of power by a gear 34 on said shaft meshing with a pinion 35 fixed on a shaft 36 with a drive wheel 37 loose on said shaft arranged to be coupled 65

and uncoupled to the shaft 36 by a clutch (shown in a general way at C) actuated by a lever 38 pivoted upon the framework, as at 39, and having a bifurcated portion 40 with oppositely extending pins 41 (Figure 2) engaging in an annular groove 42 of one member of the clutch. The ratio of the gearing of the driving means is such that after an increment of material has been fed into opposite ends of a tube the conveyer is rotated to present the tube to a succeeding pocket, the tubes being advanced in progressive sequence to the successive pockets until filled when they are ejected by the further rotation of the conveyer. 70 75 80

The tubes as they are advanced to the successive pockets and successive increments of material are fed thereinto become progressively filled to an increasing extent and to compensate for this progressive filling of 85 a tube or tubes material feeding means having a progressive decrease of material feeding movement is provided. This feeding means comprises a series of plungers 44 of nine plungers to each series one for each of the two series of pockets carried by the brackets 12, one end of said plungers being 90 slidably mounted in perforations in plates 45 fixed to the brackets with the openings concentric with the recesses 19 and in perforations in actuators 46 reciprocably mounted on the rods 13. Material feeding movement is imparted to the plungers by the actuators 46 by said actuators engaging with abutments in the form of collars fixed upon 100 the plungers, and the plungers are retracted by the actuators engaging with abutments 48 fixed upon the plungers at the side of the actuator opposite to the abutments 47, the retracting movement of the plungers being limited by the ends of the plungers 105 engaging with buffers 49 carried by brackets 50 mounted upon the standards 14. To impart movement to the plungers of progressive decreasing extent the abutments 47 are 110 mounted upon the plungers in successive stepped relation as shown in Figures 1 and 5 whereby the abutment 47 of the first plunger of each series of plungers is engaged by the actuators and movement imparted 115 thereto and the abutments 47 of the successive plungers are engaged successively by the actuators and thereby impart movement to the successive plungers of progressive decreasing extent. In the reverse movement 120 of the actuators they engage with the abutment 48 imparting retracting movement to the plungers.

The plunger actuators are operated by levers 51 pivotally supported at one end 125 upon the base B, as at 52, with the upper end bifurcated and engaging between a pair of ears 53 of lugs on the actuators and the bifurcation engaging a pin 54 engaging at opposite ends in perforations in the lug 130

ears 53. The levers are actuated by cranks consisting of crank pins 55 eccentrically carried between the heads of disks 56 fixed to shafts 57 journalled at opposite ends in 5 bearings 58 fixed to the standards 14, the crank pins being connected to the levers by rods or links 59. The crank disk carrying shafts are rotated by gears 60 on said shafts meshing with gears fixed to shafts 62 jour- 10 nalled in bearings fixed to the base and operatively connected to the shaft 33 to be driven thereby by bevelled pinions 64 on said latter shaft meshing with bevelled pinions 65 on the shaft 62. The gearing for the 15 plunger actuating levers 51 are so timed that the movement of the tube conveyer is alternate with the material feeding movement of the plungers.

As stated it is an object of the invention 20 to so construct and arrange the material receiving pockets 21 so that the material will be delivered from the hopper to said pockets during the retracting movement of the material feeding plungers and shut off 25 from the hopper outlets during the material feeding movement of the plungers to prevent any of the material in the pockets from being delivered back into the hopper. For this purpose the pockets are in the form of 30 tubes open at both ends as shown in Figure 8 with a portion of the wall cut away, as at 67, to provide an opening in the side of the tube through which to deliver the material to the pockets. These pockets are rotatably 35 mounted in the recesses 19 of the segmental portion of the brackets 12 and arranged to be actuated so that the open side of each of the pockets is presented to the hopper outlets during the retracting movement of the 40 plungers 44 to permit the material from the hopper to fall into the pockets, and rotatably adjusted just previous to the material feeding movement of the plungers to interpose the wall of the pockets between the 45 hopper outlets and the openings in the side of the tubes which are closed by the wall of the recesses 19 in the brackets 12. To rotatably adjust the pockets each pocket has a pinion 68 mounted thereon with which racks 50 in the form of toothed segments 69 mesh, said racks being carried by one arm 70 of a bell crank lever pivotally mounted upon the standards 15, as at 71, to have oscillatory movement, the other arm 72 of the levers 55 being connected by links 73 to arms 74 pivotally supported, as at 75, upon the standards 15, the other end of the arms carrying rollers 76 to co-operate with cams 77 fixed upon the shaft 33. To impart positive os- 60 cillatory movement to the pocket actuating racks 69 a second arm 78 is provided pivotally supported, as at 79, said arms having a link connection 80 with the arms 74, the arms 78 also carrying rollers at their free ends to co-operate with the cams 77 sub-

stantially at a point diametrically opposite to the cam rollers 76. It will be obvious that the arms 74 will positively move the pocket actuating racks in one direction and the other arms 78 will positively move said racks 70 in an opposite direction. The pockets are held against longitudinal movement in one direction by collars 83 fixed on the pockets and in the opposite direction by the plates 45.

To regulate the flow of the material from 75 the hopper outlets to the material receiving pockets 21 and thereby deliver predetermined quantities of material to said pockets adjustable means are provided to shut off and vary the area of the hopper outlets. 80 This means comprises gates in the form of plates 84 to slidably engage in openings between the hopper outlets and the segmental portion of the brackets 12, and manually adjusted into and out from the hopper by a 85 hand grip fixed in the plates exterior of the hopper outlets.

To agitate the material in or at the hopper outlets shafts 86 extending transversely of 90 said outlets are provided, said shafts carrying radially extending material agitating fingers or blades 87 to be passed through and agitate the material by the rotation of the shafts. The agitator shafts are rotated from the shaft 33 by belts 88 passing around 95 pulleys 89 on the agitator shafts and pulleys 90 on the shaft 33.

As stated the successive material feeding 100 plungers 44 have movement imparted thereto by the actuators 46 of progressive decreasing extent during the movement of the actuators forward or in a direction toward the material receiving pockets 21, and when said plungers are moved to the limit of their forward movement the plungers 105 will have been moved to an extent substantially as shown in full lines in Figure 5 with the material packed into the tubes 21 as shown by stippling in the tubes in section, and when the actuators have been moved 110 backward or retracted to their full extent the plungers will be in the position indicated in dotted lines at the right of Figure 5 with the ends of the plungers engaging the buffers 49.

The tubes 22 are intermittently advanced by the turret and alternately with the movement of the material feeding plungers, and in this movement of the turret empty tubes are automatically fed thereto from a chute 120 92 (Figures 2 and 3) and the filled tubes are delivered or discharged from the turret to a discharge chute 93 and delivered from the latter to a suitable receptacle or bin.

While there has been described and illustrated in the drawings specific means and arrangement of parts to carry out the invention it is to be understood that various changes may be resorted to without departing from the scope of the invention, and 125 130

that portions of the invention may be used without others.

Having thus described my invention I claim:

- 5 1. In apparatus for packing comminuted material in a tube, a tube carrier, a series of reciprocable plungers arranged at each end of the tube, and means to impart movement of progressive decreasing extent to the successive plungers of each series, said plungers being adapted to successively feed predetermined increments of material simultaneously into opposite ends of the tube. 10

15 2. In apparatus for packing comminuted material in a tube, a movable support for the tube; a series of reciprocable plungers arranged at opposite ends of the tube operative to successively feed increments of material simultaneously into opposite ends of the tube; means to impart movement of progressive decreasing extent to the successive plungers of each series; and means to move the tube support alternately with the material feeding movements of the plungers to 20 present the tube in sequence to the successive plungers for the purpose specified. 25

30 3. In apparatus for packing comminuted material in a tube, a support for the tube, means located at opposite ends of the tube to receive predetermined quantities of the material to be packed in the tube, and a series of plungers arranged at opposite ends of the tube the successive plungers of each series arranged to have progressive decreasing extent of movement imparted thereto to successively deliver material from said material receiving means simultaneously to opposite ends of the tube. 35

40 4. In apparatus for packing comminuted material in a tube, a movable support for the tube; a series of pockets to receive predetermined quantities of material arranged at opposite ends of the tube in line with the path of movement of the tube upon the support and to which pockets the tube is successively presented; a series of plungers arranged in alinement with each series of pockets, the successive plungers of each series having a progressive decreasing extent of movement and adapted to deliver material from the successive pockets in sequence and simultaneously into opposite ends of the tube. 45

50 5. In apparatus for packing comminuted material in a tube, a movable support for the tube; a series of pockets to receive predetermined quantities of material arranged at each end of the tube in the path of movement of the tube upon the support; means to intermittently move the tube support to present the tube to the successive pockets; a series of plungers arranged in alinement with each series of pockets to deliver material from the successive pockets in sequence and simultaneously to opposite ends of the tube. 55

60 6. In apparatus for packing comminuted material into tubes, a movable support for a series of tubes; a series of material receiving pockets arranged in the path of movement and at opposite ends of the tube carried by the support; means to intermittently move the support to present the successive tubes in sequence to the successive pockets; and means to deliver the material from the pockets as successive increments simultaneously to opposite ends of the tubes, said means having progressive decreasing extent of movement for the purpose specified. 65

70 7. In apparatus for packing comminuted material into tubes, a movable support for a series of tubes; a series of material receiving pockets arranged in the path of movement and of opposite ends of the tube carried by the support; means to intermittently move the support to present the successive tubes in sequence to the successive pockets; and two series of plungers arranged in alinement with the pockets to deliver the material from the pockets simultaneously into opposite ends of the tubes, the successive plungers of each series having progressive decreasing extent of movement for the purpose specified. 75

80 8. In apparatus for packing comminuted material into tubes, a movable support for a series of tubes; a series of material receiving pockets arranged in the path of movement at opposite ends of the tubes carried by the support; means to intermittently move the support to present the successive tubes in sequence to the successive pockets; two series of plungers arranged in alinement with the pockets to deliver the material from the pockets simultaneously into opposite ends of the tubes, the successive plungers of each series having progressive decreasing extent of movement; and means to intermittently move the tube support alternately with the material delivery movement of the plungers to present the successive tubes in sequence to the successive pockets for the purpose specified. 85

90 9. In apparatus of the class specified, a pair of members each member having a series of material receiving pockets in spaced and alined arrangement; a hopper arranged to deliver material to said pockets; a movable tube support interposed between said members arranged to carry tubes and position the tubes in axial alinement with the pockets; plungers to deliver the material from said pockets simultaneously into opposite ends of the tubes; and means to im- 95

130 130

part movement of progressive decreasing extent to the successive plungers for the purpose specified.

10. In apparatus of the class specified, a pair of members each member having a series of material receiving pockets in spaced and alined arrangement; a hopper arranged to deliver material to said pockets; a movable tube support interposed between said members arranged to carry tubes and position the tubes in axial alinement with the pockets; plungers to deliver the material from said pockets simultaneously to opposite ends of the tubes; abutments arranged on said plungers; and actuators for said plungers adapted to have movement relative to said plungers and engage the plunger abutments to actuate the plungers, said abutments being arranged upon the successive plungers to be engaged by the actuators in progressive sequence to impart movement to the successive plungers of progressive decreasing extent for the purpose specified.

11. In apparatus of the class specified, a pair of members each member having a series of material receiving pockets in spaced and alined arrangement; a hopper arranged to deliver material to said pockets; a movable tube support interposed between said members arranged to carry tubes and position the tubes in axial alinement with the pockets; plungers to deliver the material from said pockets simultaneously to opposite ends of the tubes; abutments arranged on said plungers; reciprocal actuators for said plungers adapted to engage the plunger abutments to actuate the plungers, said abutments being arranged upon the successive plungers to be engaged by the actuators in progressive sequence to impart movement of progressive decreasing extent to each successive plunger; and a second abutment on each of said plungers to be engaged by the actuators to retract the plungers.

12. In apparatus of the class specified, a pair of members each member having a series of material receiving pockets in spaced and alined arrangement; a hopper arranged to deliver material to said pockets; a movable tube support interposed between said member arranged to carry tubes and position the tubes in axial alinement with the pockets; plungers to deliver the material from said pockets simultaneously to opposite ends of the tubes, abutments arranged on said plungers; reciprocal actuators for said plungers adapted to engage the plunger abutments to actuate the plungers, said abutments being arranged upon the successive plungers to be engaged by the actuators in progressive sequence to impart movement of progressive decreasing extent to each successive plunger; and means to intermittently advance the tube support and

alternately with the material delivering movement of the plungers for the purpose specified.

13. In apparatus of the class specified a pair of members each member having a series of material receiving pockets with the pockets of one member in spaced and alined arrangement with the pockets of the other member; a hopper arranged to deliver material to said pockets; a rotatable tube conveyor interposed between said members arranged to carry tubes and position the tubes in axial alinement with the pockets; plungers to deliver material from said pockets simultaneously to opposite ends of the tubes; abutments arranged on said plungers; reciprocal actuators for said plungers adapted to engage the plunger abutments to actuate the plungers, said abutments being arranged upon the successive plungers to be engaged by the actuators in progressive sequence to impart movement of progressively decreasing extent to the successive plungers; and means to intermittently rotate the tube carrying turret a predetermined extent and alternately with the movement of the plunger actuators to present a tube carried by the turret in progressive sequence to the successive pockets for the purpose specified.

14. In apparatus for the purpose specified, two series of parallel spaced and alined material receiving pockets; a support for a series of tubes with one end of the tubes in register with one series of pockets and the opposite ends of the tubes in register with the other series of pockets; plungers to deliver material from the pockets into opposite ends of the tubes; reciprocal actuators for said plungers; and means to reciprocate said plunger actuators comprising a pivoted lever for each actuator, rotatable cranks, and rods connecting said levers to the cranks.

15. In apparatus of the class specified, a material carrying hopper having an outlet; pockets to receive material from said hopper comprising a series of tubes arranged in parallel relation in the arc of a single at the hopper outlet, and each tube having a portion of the side wall cut away to provide an opening through which to receive material from the hopper; a support in which the pockets are rotatably mounted; plungers to deliver material from said pockets; a pinion mounted on each of the pocket tubes; and an oscillatory toothed sector meshing with the tube pinions operative to oscillate said pockets to present the opening in the pockets to the hopper during the retracting movement of the plungers and to shut off said openings from the hopper during the material delivering movement of the plungers.

16. In apparatus of the class specified, a material carrying hopper having an outlet; tubular pockets arranged in parallel rela-

tion at the hopper outlet having openings in the side wall through which to receive material from the hopper; means in which said pockets are rotatably mounted; plungers to deliver material from said pockets; and means to rotatably adjust said pockets to present the openings therein to the hopper outlet during the reciprocating movement of the plungers and to position the pockets

10 to present the wall of the pockets to the

hopper outlet during the material delivery movement of the plungers, comprising a toothed wheel mounted on each of said pockets and a reciprocable rack meshing with the teeth of said wheels.

15

Signed at Brooklyn, in the county of Kings, city and State of New York, this 13th day of April, 1921.

ARON JOHNSON.
